US0D1037313S

(12) **United States Design Patent** (10) **Patent No.:** **US D1,037,313 S**
(45) **Date of Patent:** **** Jul. 30, 2024**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Taylor Gerard Carrigan**, San Francisco, CA (US); **Aled Williams**, Llandeilo (GB)

(73) Assignee: **Apple Inc.**, Cupertino, CA (US)

(**) Term: **15 Years**

(21) Appl. No.: **29/796,730**

(22) Filed: **Jun. 25, 2021**

(57)

CLAIM

The ornamental design for a display screen or portion thereof with graphical user interface, as shown and described.

DESCRIPTION

FIG. 1 is a front view of a display screen or portion thereof with graphical user interface showing the claimed design; and,

FIG. 2 is a front view of a second embodiment thereof. The broken lines in the figures show a display screen or portion thereof, and form no part of the claimed design.

1 Claim, 1 Drawing Sheet

See application file for complete search history.
